BERNARD STEINMETZ, OF PARIS, FRANCE.

Letters Patent No. 49,207, dated August 1, 1865; reissue No. 3,765, dated December 14, 1869.

IMPROVED CARPET-BAG-LOCK.

The Schedule referred to in these Letters Patent and making part of the same.

To all whom it may concern:

Be it known that I, BERNARD STEINMETZ, of the city of Paris, in the Empire of France, have invented a new and improved Spring-Lock for Satchels, Carpet-Bags, &c.; and I do hereby declare that the following is a full and exact description of the same, reference being had to the accompanying drawings, and to the letters of reference marked thereon.

Figure I represents a frame for a satchel, with the spring-lock in section.

Figure II is an outside view of the lock, and of part of the frame.

Figure III shows a section of the frame, open, taken near the lock.

Similar letters represent similar parts.

In the accompanying drawings—

A represents one part of the jaw-frame, to which the lock C is attached, and B is the other part of said frame, bent in any desired form, and jointed together at their lower ends, at a, in the usual manner.

In the lock-case a lever, D, is arranged, turning on a fixed centre, n, fast in the said casing, and acted upon by a spring, w, so as to press said lever downward.

A projection, m, is attached to this lever D, passing through the frame A, and sufficiently long to pass through the staple h attached to the inside of the frame B.

On the outside of the lock-casing C, some projecting part or figure T, an eagle, as represented in the drawing, (see Fig. II,) is arranged and attached to this lever D, by means of a bolt or pin passing through a suitable slot, 2, in the side of the casing, by which arrangement the lever D can be forced upward, against the action of the spring w, so as to bring the projection m clear of the staple h, for the purpose of opening the frame A B, and consequently the bag or satchel.

The lower end of the projection m, on the side next to the frame B, or to the staple h, is made slanting, so as to allow the staple h to force said lever D upward, when pressed against said projection m, when

the satchel requires to be shut or closed, until the staple h has passed the projection, when the action of the spring w will again force said lever D downward, and into the opening in the staple, and thereby keep the satchel-jaws or frame, &c., closed.

Near the end of the lever D, a tumbling-bolt, v, is arranged, turning on a fixed centre, and acted upon by a spring, s. This bolt v is operated by means of a key inserted through the key-hole x, in such a manner as to bring one of its projections, 3, over the end of the lever D, and in which position the action of the spring s will hold the same, thereby locking the lever D, and consequently the bag or satchel, until the action of the key removes again this projection on the tumbling-bolt from the end of said lever, and thereby unlocks the same.

N is a small ornamental knob or projection, attached to the frame B, to be taken hold of when the bag or satchel requires to be pulled open.

I have represented the figure of an "eagle" as a shield-knob, and use that form, and therefore prefer to give it that name; but any equivalent device or form, which covers the slot, may be used in its stead, and the eagle may be used on other lock-devices, of different construction, without infringing my invention.

What I claim as my invention, and desire to secure by Letters Patent, is—

The pivoted spring-lever D, with its catch-projection m, and the spring tumbling-block or bolt v, operated by a key, combined and arranged substantially as herein described, when applied to the jaws of a satchel, bag, or portmanteau, for the purpose specified.

Also, the combination of the "eagle," or shield-knob T, constructed so as to cover the slot 2 in the lock-case C, the catch m of the spring-bar D, and the staple h of the jaw-frame B, as herein specified.

BERNARD STEINMETZ.
